CLAMPING DEVICE FOR WEFT REPLENISHING LOOMS

Richard Greenleaf Turner, Worcester, Mass., assignor to Crompton & Knowles Loom Works, Worcester, Mass., a corporation of Massachusetts

Application March 22, 1932, Serial No. 600,468

15 Claims. (Cl. 139—256)

This invention relates to looms in which the supply of weft or filling is automatically replenished, and relates more particularly to that type of weft replenishing loom in which an exhausted or substantially exhausted shuttle is automatically ejected and a fresh shuttle substituted therefor. Such looms are largely used for weaving silk and rayon and other fine fabrics in which the slightest variation in weft tension is noticeable and objectionable.

In certain looms of this type, the shuttle is changed at back center while the lay is at rest with the shed fully open and while the last inserted or out-going weft thread rests loosely on the lower warp shed. It is found that this out-going weft thread sometimes becomes wrapped about or otherwise involved with the out-going shuttle in such a way that the weft thread is substantially tensioned by the falling shuttle.

When the shed closes upon a weft thread which has thus been additionally tensioned, a difference in the weave is produced which is distinctly visible in the sheen of a silk or rayon fabric and which is considered a substantial defect therein. It is the object of my present invention to provide a device which will clamp the out-going weft thread adjacent the selvage as a substantially exhausted shuttle is being ejected, and which will thus maintain normal tension in that portion of the out-going weft which rests in the warp shed.

My invention further relates to arrangements and combinations of parts which will be herein-after described and more particularly pointed out in the appended claims.

A preferred form of the invention is shown in the drawings, in which

Fig. 1 is a plan view of portions of a shuttle changing loom embodying my improvements;

Fig. 2 is a front elevation of the parts shown in Fig. 1;

Fig. 3 is a diagrammatic plan view illustrating the ejection of the shuttle;

Fig. 4 is a sectional end elevation of parts of the loom, taken substantially along the line 4—4 in Fig. 1, and

Fig. 5 is a sectional end elevation, taken along the line 5—5 in Fig. 1.

Referring to the drawings, I have shown portions of a weft replenishing loom of the general type shown in the prior patent to Jackson No. 1,133,802, issued March 30, 1915. In this type of loom, the lay 10 is provided with a fixed back box plate 11 and with a front box plate 12 mounted on arms 13 pivoted on a rod 14 and connected

by a link 15 (Fig. 4) to actuating mechanism (not shown) by which the front box plate 12 may be raised when a shuttle change is indicated.

A pusher or ejector 17 is mounted to swing forward through an opening in the back box plate 11 and to push the shuttle S forwardly off of the lay while the front box plate 12 is in raised position.

The ejector 17 is pivoted on a cross rod 18, supported in fixed arms 20 extending forwardly from the brackets 21 which support the rod 14 on which the arms 13 are pivoted.

A contact screw 22 is adjustable in a forwardly extending portion 23 of the ejector 17 and is engaged by an upper surface of the front box plate 12 as the box plate is raised to permit a change of shuttles.

When the front box plate 12 is thus raised, the ejector 17 is swung forward to the dotted line position indicated in Fig. 4 and the shuttle S is pushed forward and outward as also indicated in dotted lines in Fig. 4. A spring 25 holds the front box plate 12 normally in lowered operative position, and a spring 26 normally holds the ejector 17 retracted.

The parts thus far described are of a usual commercial construction and operate substantially as described in the Jackson patent. In themselves they form no part of my present invention, which relates particularly to means for clamping the weft thread W during the ejection of the shuttle S from the shuttle box.

For this purpose I provide a clamping member or plunger 30 movable vertically in a fixed guideway or bearing 31 (Figs. 2 and 5) and having a pin and slot connection at its upper end to a lever 33 pivoted at 34 to a bracket 35 mounted in fixed position on the top of the back box plate 11. A friction surface 36 (Fig. 1) on the hub of the lever 33 engages a corresponding friction surface on the bracket 35 and is held in firm frictional contact therewith by a compression spring 37 mounted on the front end of the pivot stud 34.

The upper end of the lever 33 extends over one of the arms 13 previously described which raise and lower the front box plate 12. A spring plate 40 is mounted under the upper end 38 of the lever 33 and provides a slightly resilient engagement with the arm 13. A pad 42 of leather or other suitable cushion material is preferably secured to the under face of the clamping member 30.

A cam member 44 (Fig. 4) is mounted in fixed position at the rear of the shuttle storage maga-

zine M and engages the upper end 38 of the member 33 as the lay 10 moves forward after the exhausted shuttle S has been ejected.

The operation of the clamping device is as follows:

After an indication of substantial weft exhaustion, the arms 13 and front box plate 12 are moved upward by the actuating link 15 and during the middle portion of the upward movement of the front box plate 12 the contact screw 22 is engaged and the ejector 17 is moved forward.

During this forward movement of the ejector 17, one of the arms 13 engages the spring plate 40 and depresses the clamping member 30 on the weft thread W, which thread lies in the open warp shed and has been moved forward under the clamping member 30 by the action of the ejector 17.

The weft thread W will thus be clamped and firmly held by the clamping member 30, as indicated in Fig. 5, and the parts will be held frictionally in this position until the lay 10 approaches its extreme forward position. The upper end 38 of the lever 33 will then engage the fixed cam member 44 (Fig. 4) and will be moved thereby to the initial inoperative position indicated in Fig. 2.

It will thus be evident that a firm clamping pressure is applied to the weft thread W between the selvage of the cloth and the exhausted shuttle S, so that any increase in weft tension caused by entangling the weft with the falling shuttle cannot be communicated to that portion of the weft which extends through the shed and rests freely on the lower set of warps.

Consequently normal weft tension is maintained in that portion of the weft between the cloth selvages, regardless of changes in weft tension in that portion of the weft extending from the clamping member 30 to the ejected shuttle S. The quality of the fabric is thus substantially improved and variations in appearance caused by slight differences in weft tension are avoided.

Having thus described my invention and the advantages thereof, I do not wish to be limited to the details herein disclosed, otherwise than as set forth in the claims, but what I claim is:

1. In a loom, shuttle-changing mechanism, means to clamp the out-going weft thread at a point between the out-going shuttle and the adjacent cloth selvage during ejection of said shuttle, and actuating devices for said clamping means, operable in timed relation to the movement of the shuttle-changing mechanism.

2. In a fly shuttle loom, shuttle-changing mechanism, operating substantially at back center and means to clamp the out-going weft thread to the lay during shuttle ejection.

3. In a fly shuttle loom, shuttle-changing mechanism, and means to clamp the out-going weft thread to the lay during shuttle ejection and at a point in front of the path of the shuttle and in front of the normal position of the weft thread.

4. In a fly shuttle loom, shuttle-changing mechanism, and means to clamp the out-going weft thread to the lay during shuttle ejection, said clamping means becoming operative when the shuttle has been given a partial forward ejecting movement.

5. In a loom, shuttle-changing mechanism, and means to clamp the out-going weft thread between the out-going shuttle and the adjacent cloth selvage during ejection of said shuttle, said

clamping means being moved directly by said shuttle-changing mechanism after a partial operative movement of said mechanism.

6. In a loom, shuttle-changing mechanism, and means to clamp the out-going weft thread between the out-going shuttle and the adjacent cloth selvage during ejection of said shuttle, said clamping means including a yielding element engageable by said shuttle-changing mechanism.

7. In a loom, shuttle-changing mechanism, a normally inoperative weft-clamping device movable by said mechanism to clamping position on the initiation of shuttle replacement, and friction means to hold said device in clamping position after movement by said shuttle-changing mechanism.

8. In a loom, shuttle-changing mechanism, a normally inoperative weft-clamping device movable by said mechanism to clamping position on the initiation of shuttle replacement, friction means to hold said device in clamping position after movement by said shuttle-changing mechanism, and means to restore said clamping device to normally inoperative position.

9. In a loom, shuttle-changing mechanism, a normally inoperative weft-clamping device movable by said mechanism to clamping position on the initiation of shuttle replacement, friction means to hold said device in clamping position after movement by said shuttle-changing mechanism, and positive cam means effective to return said clamping device to normal inoperative position as the lay approaches front center.

10. In a fly shuttle loom, shuttle changing mechanism operating while the lay is at rest, and means to clamp the last inserted weft thread to the lay, said clamping means being rendered operative after the lay is brought to rest.

11. In a fly shuttle loom, a single shuttle box at the weft replenishing end of the lay, means to initiate weft replenishment with the lay substantially at back center and after the shuttle is boxed at the weft replenishing end and while the warp shed is open, and a clamping device actuated by said replenishing means and effective when actuated to maintain normal tension in that portion of the last-inserted pick of weft which is in the open warp shed during such weft replenishment.

12. In a fly shuttle loom having a plurality of warp threads forming an open shed, a single shuttle box at the weft replenishing end of the lay, means to replenish the weft supply with the lay substantially at back center and after the shuttle is boxed at the weft replenishing end and while the warp shed is open, and a clamping device actuated by said replenishing means and effective when actuated to prevent an increase in tension in that portion of the last-inserted weft thread which is in the open warp shed during weft replenishment.

13. In a loom, shuttle changing mechanism operating to eject a shuttle substantially at back center and while the warp shed is open, and means to clamp the out-going weft thread on the lay adjacent the shuttle box and at a point between the out-going shuttle and the adjacent cloth selvage during ejection of said shuttle from the lay.

14. In a loom, shuttle changing mechanism operating to eject a shuttle substantially at back center and while the warp shed is open, and means on the lay effective to prevent the ejected shuttle from altering the tension on that part

of the last-inserted weft thread which is in the open warp shed during ejection of said shuttle from the lay.

15. In a fly shuttle loom, shuttle changing mechanism operating to eject a shuttle while the warp shed is open, and means on the lay

effective to prevent the ejected shuttle from altering the tension on that part of the last-inserted weft thread which is in the open warp shed during ejection of said shuttle from the lay.

RICHARD GREENLEAF TURNER.
